UNITED STATES PATENT OFFICE.

ALBERT KLINE, OF CHICAGO, ILLINOIS.

FREIGHT-CAR LOCK.

1,424,168.

Specification of Letters Patent. Patented Aug. 1, 1922.

Application filed May 20, 1920. Serial No. 382,697.

To all whom it may concern:

Be it known that I, ALBERT KLINE, a citizen of the United States, residing at Chicago, in the county of Cook and State of Illinois, have invented a certain new and useful Improvement in Freight-Car Locks, of which the following is a specification.

My invention relates to improvements in freight car locks and has for its object to 10 provide a new and improved form of lock which will be secure and at the same time, cheap to manufacture and easy to operate and which will not interfere with the sliding back of the door when it is desired to 15 open it. Experience has shown that in the past when freight car doors were locked and sealed only at one side, it was possible for thieves to wedge the back edge of the door away from the side of the car without disturbing the lock and thus gain access to the 20 freight within the car, and my invention obviates that possibility. My lock may be made of steel, iron or any other suitable material which will be strong enough to make 25 the lock secure.

My invention is illustrated more or less diagrammatically in the accompanying drawings wherein:

Figure 1 is a side elevation of the freight 30 car door, in the closed position on the car;

Figure 2 is a section along the line 2—2 of Figure 1;

Figure 3 is a front elevation of the lock;

Figure 4 is a section along the line 4—4 of 35 Figure 3;

Figure 5 is a section along the line 5—5 of Figure 3;

Like parts are indicated by like characters in all the drawings.

A is a sliding freight car door having the lock plate A' at the back edge thereof. The lock A' is fastened to the door at one end by means of a bolt A² which projects far enough out from the door frame to allow the lock to swing down when the car door is opened. The bolt is tightened in position on the door frame by means of a nut A³ and the shoulder A⁴ resting on the washer A⁵ allows the head end of the bolt to project sufficiently to permit the lock to swing down when the door is opened as above referred to. The lock is fastened at its other end to the car body by means of a bolt A⁶ which has an eye shaped head A⁷. The bolt eye is located in a recess in the car wall and the bolt is held in position by a

nut and washer. The lock plate A' is slotted as at A⁸ to engage the eye A⁷ and is so shaped that it has a plurality of perpendicular parts, one parallel the car door the next 60 perpendicular thereto, a third parallel with and adapted to rest against the car wall and the next perpendicular to it and adapted to penetrate the recess, and the last, the slotted part parallel the first and adapted to 65 pass over the bolt eye.

C is the usual form of hasp fastened at one end to the car door by means of the staple C', and slotted at the other end in the usual manner to engage the staple C². 70 The hasp is held in place on the staple by the pin C³.

The use and operation of my invention are as follows:

The lock plate is permanently attached to 75 the car door by a bolt which is allowed to project sufficiently to leave play for the lock plate to swing down perpendicularly on the door when not in use. When the door is closed and it is desired to lock it 80 more securely than, and in addition to the ordinary hasp and staple lock on the forward portion of the door, my lock plate is slipped over the eye bolt, and locked in position by a quarter turn of the eye bolt. 85 This bolt is sunk into a groove in the car frame just deep enough to permit the top of the bolt to come flush with the outer surface of the car frame and thus does not interfere with the opening of the sliding door. The pin is then slipped through the eye of the bolt and the seal is attached to 90 the lower position of the pin. This makes it impossible to wedge open either side of the 95 car door without breaking the seals on the locks.

I claim:

1. A lock plate for freight car doors consisting of a unitary plate comprising a plurality of perpendicular sections at right angles with each other and adapted to engage the several surfaces of the freight car door and the car body, one part of the lock plate slotted and adapted to penetrate a recess in 100 the car body.

2. A lock plate for freight car doors consisting of a plurality of perpendicular sections at right angles with each other and adapted to engage the several surfaces of the 110 freight car door and the car body one part of the lock plate slotted and adapted to

penetrate a recess in the car body, an eye bolt therein adapted to engage the slot in the lock plate.

3. A lock plate for freight car doors consisting of a plurality of perpendicular sections at right angles with each other and adapted to engage the several surfaces of the freight car door and the car body one part of the lock plate slotted and adapted to 5 penetrate a recess in the car body, an eye bolt therein adapted to engage the slot in the lock plate and hold said plate firmly in position.

4. A unitary lock plate comprising five 15 right angled parts the first adapted to engage the front surface of a freight car door, the next the back edge of the door, the next the front surface of the car body adjacent it, and the last two adapted to penetrate a 20 recess in the car wall.

5. A unitary lock plate comprising five right angled parts the first adapted to engage the front surface of a freight car door, the next the back edge of the door, the next 25 the front surface of the car body adjacent it, and the last two adapted to penetrate a recess in the car wall, the fifth part of the lock plate being slotted to engage an eye of a bolt in the recess of the car body.

30 6. A lock plate comprising five right angled parts the first adapted to engage the front surface of a freight car door, the next the back edge of the door, the next the front surface of the car body adjacent it, and the 35 last two adapted to penetrate a recess in the car wall, the fifth part of the lock plate being

slotted to engage an eye of a bolt in the recess of the car body said bolt eye being adapted to turn to secure the lock plate firmly upon the door and car wall. 40

7. A lock plate comprising five right angled parts the first adapted to engage the front surface of a freight car door, the next the back edge of the door, the next the front surface of the car body adjacent it, and the 45 last two adapted to penetrate a recess in the car wall, the fifth part of the lock plate being slotted to engage an eye of a bolt in the recess of the car body, said bolt eye being adapted to turn to secure the lock plate firmly upon the door and car wall, a pin 50 adapted to penetrate the eye of the bolt and to be sealed at its lower end.

8. A lock plate for a freight car door consisting of a unitary plate comprising a plurality of sections at angles to each other and adapted to engage the several surfaces of the freight car door and the car body, one part of the lock plate slotted and adapted to penetrate a recess in the car body. 55

9. A lock plate for a freight car door consisting of a unitary plate comprising a plurality of sections at angles to each other and adapted to engage the several surfaces of the freight car door and the car body, one part of the lock plate slotted and adapted to penetrate a recess in the car body, an eye-bolt therein adapted to engage the slot in the lock plate. 60

Signed at Chicago county of Cook and 70 State of Illinois, this 3rd day of May 1920.

ALBERT KLINE.
